V. GUINZBURG.
FLOTATION DEVICE.
APPLICATION FILED DEC. 18, 1920.

1,383,624.

Patented July 5, 1921.

UNITED STATES PATENT OFFICE.

VICTOR GUINZBURG, OF NEW YORK, N. Y., ASSIGNOR TO I. B. KLEINEERT RUBBER COMPANY, OF NEW YORK, N. Y., A CORPORATION OF NEW YORK.

FLOTATION DEVICE.

1,383,624.

Specification of Letters Patent. Patented July 5, 1921.

Application filed December 18, 1920. Serial No. 431,636.

To all whom it may concern:

Be it known that I, VICTOR GUINZBURG, a citizen of the United States, and a resident of the city, county, and State of New York, 5 have invented a certain new and useful Improvement in Flotation Devices, of which the following is a specification.

This invention relates to a flotation or swimming device in the nature of an inflatable bag having means for securing it to the body and adapted to support the body while in the water.

The object of this invention is to provide a device which will be simple in construction 15 and economical in manufacture, which will be effective in operation and which can be worn without interfering with the movement of the body while swimming.

A further object of this invention is to 20 provide a device of this character which can be folded compactly when deflated so that it will occupy but little space.

With these objects and other objects in view, I have devised the particular arrangement of parts hereinafter set forth and more particularly pointed out in the claims 25 appended hereto.

Reference is to be had to the accompanying drawing forming a part hereof in 30 which—

Figure 1 is a plan view partly in section, of a flotation device made in accordance with my invention,

Fig. 2 is a transverse sectional view of the 35 same on the line 2—2 of Fig. 1,

Fig. 3 is a fragmentary view of one corner of the device showing the construction of the inflation valve;

Fig. 4 is a perspective view of a corner 40 of the inner inflatable casing showing one of the securing tabs; Fig. 5 is a sectional view on the line 5—5 of Fig. 1 looking in the direction of the arrows; and

Fig. 6 is a sectional view on the line 6—6 45 of Fig. 1, looking in the direction of the arrows.

Throughout the various views of the drawing, similar reference characters designate similar parts.

50 In the preferred embodiment of my invention, as disclosed in the accompanying drawing 1 indicates an outer casing which is preferably made of any textile material and which is substantially rectangular in shape.

55 This casing may be made by transversely

folding a section of material and securing three of the edges together. The edges of the bag 1 may be secured together by stitching 2. At 3 is shown an inner impervious, inflatable bag which is preferably made of sheet rubber and is adapted to be inflated to distend the outer casing. The inner casing 3 is preferably of a rectangular form to conform to the outer casing and it has its edges united in any suitable manner, 60 and these edges are reinforced by suitable binding strips 4.

Projecting from suitable points on the inner casing 3 are a number of securing tabs 5 which, in this instance, project from 70 the four corners of the bag. These tabs 5 enable the interior casing 3 to be secured in position within the outer bag 1, whereby it retains its position within the outer casing. The tabs 5 may be secured to the 75 outer casing 1 in any desired manner and I have shown them secured by the edge stitches 2 of the outer bag or casing 1. This construction is disclosed in Fig. 6.

At 6 is shown the inflation valve which 80 consists of a collapsible or flexible rubber tube 7 which extends into the interior of the inner casing 3. This tube 7 is cemented or otherwise secured to the inner casing 3 and secured within the tube 7 is a threaded 85 sleeve 8. The sleeve 8 projects on the outside of the outer casing 1 and is adapted to receive a closure cap 9 to prevent the escape of air from the interior casing 3.

It will be seen that the inner bag 3 may 90 be inflated by means of air blown through the sleeve 8 and through the flexible or collapsible tube 7. To prevent the escape of air while the cap 9 is being placed in position, the flexible or collapsible tube 7 may 95 be squeezed or pressed together.

At 10 are the tapes which are utilized to secure the device about the body of the user. These tapes are attached to the exterior bag 1 through the medium of the tabs 11. The 100 tabs 11 each consist of a section of material folded upon itself with the tapes 10 lying between the folded portions and held therein by cementing or stitching.

If desired, however, the tabs 11 may 105 consist of two sections of material adhesively secured together or stitched together with the ends of the tapes 10 secured between them.

It will be seen that the two sections of each 110

tab 11 embrace a portion of the outer casing 1 between them and are secured to said casing 1 by means of stitches 12, 13 and 14. This particular construction affords a strong and 5 substantial method of attaching the tapes in position without the necessity for perforating the interior inflatable bag.

The completed double bag is substantially 10 of rectangular form and is secured to the body by means of the tapes 10. The bag is freely pivotal in any direction that it may be moved in by the pressure of the water.

The outer casing 1 of the device is preferably 15 made of strong protective textile material and it acts as a protective casing for the interior casing which is preferably of soft sheet rubber and unless protected would be liable to injury.

In addition, the outer casing being non- 20 stretchable, causes the inner casing when inflated, to conform to its shape thus preventing the interior casing from being inflated to too great an extent.

The manner in which the inner casing is 25 secured in position enables the device to be constructed easily and by means of stitching, and the inner casing is easily positioned within the outer casing by the tabs 5, with all likelihood of the inner casing being punctured, avoided.

From the foregoing, it is obvious that my invention is not to be restricted to the exact embodiment shown, but is broad enough to cover all structures coming within the scope of the annexed claims.

What I claim is:

1. A device of the class described comprising an inflatable body and outer covering corresponding in shape to said inflatable body, means for securing said inflatable body in said covering, tabs pendant from the outer covering and securing tapes held within the tabs and projecting therefrom.

2. A device of the class described comprising a substantially rectangular inflatable body, tabs extending therefrom, an outer casing for said inflatable body, said inflatable body being secured within its outer casing by means of said tabs, and securing tapes attached to said outer casing.

3. A device of the class described, comprising a rectangular inexpansible bag, an expansible and inflatable casing within the same, projections extending from the corners of said inner casing and securing said inner casing within the outer casing.

Signed at the city, county and State of New York, this 16th day of December, 1920.

VICTOR GUINZBURG.
